STAPLING MACHINE

William G. Pankonin, Chicago, Ill.

Original application July 1, 1940, Serial No. 343,380. Divided and this application April 5, 1941, Serial No. 387,006

8 Claims. (Cl. 1-3)

This invention relates generally to improvements in stapling machines.

This application is a division of the copending application of William G. Pankonin, applicant herein, Serial No. 343,380, filed July 1, 1940, for "Stapling machines."

One of the objects of the invention is to provide a stapling machine of neat and simple appearance, adaptable for use as a desk type stapler, as a hand-held plier-type stapler, and as a tacker device.

The foregoing object is accomplished by constructing the stapling machine of elongated arms pivoted at one end of each by a single pintle. One arm forms a base for the support of the other arms and also carries a staple clinching anvil. Two other arms, an operating arm and a magazine arm, are interrelated to form a staple storing and driving mechanism. This driving mechanism is operable by moving the operating arm relatively toward the magazine arm. This occurs whenever the motion of the magazine arm is arrested by the base arm or material being stapled. The base arm and operating arm are designed and dimensioned so that the operator can grasp them between the palm and fingers of one hand and operate them by squeezing the hand. The base arm is also adapted to be positioned on a supporting surface so that the operator may operate the operating arm by merely applying downward pressure. To use the machine as a tacker, the base arm is provided with brackets so that it can be swung away and out from under the magazine arm. The magazine arm may then be placed directly on the material and the staple driven therein without clinching by merely pressing downwardly on the operator arm.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is a view in side elevation showing a stapling machine embodying the present invention;

Figure 2 is a sectional view in side elevation showing a stapling machine embodying the present invention, the section line meandering from the center plane to a plane just inside the side

wall of the magazine arm and back to the center plane again for sake of clarity;

Figure 3 is an exploded view in perspective showing the various parts comprising a stapling machine embodying the present invention;

Figure 4 is a sectional view in side elevation showing the stapling machine embodying the invention with the staple follower unit in retracted position;

Figure 5 is a fragmentary view in side elevation showing the stapling machine embodying the invention with the operating arm swung upwardly from the magazine arm;

Figure 6 is a sectional view taken on the line 15 6-6 of Figure 4.

Referring now to the drawings, the stapling machine generally comprises an operating or presser arm 1 overlying and interrelated with a magazine arm 2 and a base arm 3, which latter is adapted to support the stapling machine. These arms are all pivoted about the same axis.

The base arm 3 comprises an elongated, inverted, channel-like member which carries at its forward end a staple-clinching anvil 5. The anvil 5 has two differently acting clinching cavities, and is shiftable forwardly and rearwardly of the arm 3 to aline a selected one of the clinching cavities with the ejection chute. A spring 6, extending between the downwardly extending ends of the anvil 5, has an upwardly bowed portion which bears against either side of a downwardly projecting ridge 7 to urge and maintain the anvil 5 to and in one of its selected positions. At its front and rear ends the base arm 3 is provided with rubber foot pads 8 and 9. Intermediate its ends the base arm 3 is narrowed, as is evident from Figure 3, to permit it to be readily grasped in the fingers of the operator's hand when the stapling device is used as a plier-type stapler. At the rearward end of the base member 3 there are provided two parallel spaced slots 10 and 11 piercing the upper surface thereof. A supporting bracket 12 has a web portion 13 positioned below the surface of the base arm 3 and two upwardly extending flanges 14 and 15 extending through the slots 10 and 11, respectively. The web portion is spot-welded or otherwise fastened to the base arm 3 to secure the bracket 12 in position. At the upper ends of the flanges 14 and 15 there are alined apertures which receive the nutted pintles 4a and 4b.

The bottom of the base arm 3 has a cover plate 22, held by a tight frictional grip to the inner surfaces of the edges of the base arm 3. The cover

plate 22 is co-extensive with the narrow portion of the base arm 3 and furnishes a smooth portion which is easily grasped in the hands of the operator when the device is used as a plier-type of stapler.

The magazine arm 2 has a laminated core 23 upon which the staples S ride in straddle fashion, as is indicated in Figures 2 and 3. Folded longitudinally about the forward end thereof is a housing member having a front wall 24 and side walls 25 and 26. Each of the side walls has a bottom portion bent underneath and secured to the bottom of the laminated core 23. The side walls are spaced from the sides of the core 23 to form a guide for staples on the core 23. The front wall is spaced from the front end of the core 23 to form an ejection chute through which staples are driven. The top edges of the side walls 25 and 26 are provided at their forward edges with upward projections 27 and 28 which are adapted to limit the relative movement between the operating or presser arm 1 and the magazine arm 2. At the rearward edge of these projections there are rearwardly projecting teeth 29 and 30 offset outwardly from the side of the respective walls and adapted to interlock with spring-biased clips to prevent the operating arm 1 from separating from the magazine arm except at the will of the operator. At the rearward end of the sides 25 there are pintle brackets 31 and 32 having apertures in their upper ends adapted to receive the nutted pintles 4a and 4b. Staple guides 33 and 34 are inserted within the confines of the walls 25 and 26, and are secured thereto by small flush rivets or other suitable means. The guides 33 and 34 have lower inwardly projecting flanges 35 and 36, which are spaced from the top of the staples riding on the core 23. At their forward ends guides 33 and 34 are of greater height, and their corners are beveled at 37 and 38 to provide an easy entrance for the staple-driving tool carried by the operating arm 1.

On the upper edges of the guides 33 and 34, intermediate the ends thereof, are locks 39 and 40 to detachably hold the retaining bracket 44 which in turn loosely slidably holds the follower rod. Adjacent the locks 39 and 40 are pedestals 41 and 42 providing a bearing for compression springs urging the operating arm 1 away from the magazine arm 2.

The staple follower mechanism is more completely described and claimed in the aforementioned application of William G. Pankonin and forms no part of the present invention.

The operating arm 1 is formed of a single piece of sheet metal folded about the forward wall 53. The side walls extend rearwardly from the forward wall 53 and have their upper edges turned and joined by tongue and groove means, indicated at 54. At the rear of the arm 1 the sides are pierced to receive the nutted pintles 4a and 4b. The arm 1 slidably fits over the magazine arm 2 and both are pivoted to the flanges 14 and 15 by the pintles 4a and 4b. The rear portions of the sides of arm 1 are offset inwardly at the rear and slide against the inner surfaces of the flanges 14 and 15. There is sufficient clearance between the walls 25 and 26 and the walls of arm 1 to accommodate the shanks of the clips 65 and 66 therebetween. The bottom edges of the front and side walls of the arm 1 are peened inwardly, as indicated in Figure 2. A pair of springs 55 and 56 are positioned within the confines of the arm 1 and are frictionally held on guides secured to the under surface of the arm. They rest

against the upper surfaces of the pedestals 41 and 42, respectively, when the operating arm 1 is in operative position. These springs resiliently urge the operating arm 1 away from the magazine arm 2. A spring clip 57, adapted to detachably grasp and hold the sleeve 47, is soldered or otherwise secured to the top inner side of the operating arm 1 adjacent its rear end. At its top forward end the operating arm 1 is provided with a slot 58 adapted to receive a projection on the driving blade 59. A latch arm 60 is provided with a forward extension 60a adapted to pass through a crescent-shaped slot in the top of the blade 59 and enter into a similarly shaped slot 61 in the wall 53 to hold the driving blade 59 in the slot 58 and in abutment against the inner surface of the top of the operating arm 1. A small compression spring 62 is positioned between the inner surface of the forward wall 53 and the driving blade 59. The spring 62 urges the blade 59 against the shoulders formed at the base of the extension 60a and thereby flexibly maintains the blade in alignment with the ejection chute defined by the wall 24, the forward edges of the staple guides 33 and 34 and the beveled corners 37 and 38. The latch arm 60 is retained in position by a pin 63 having thereon a compression spring 64 fitting within a semi-circular hump in the latch 60. The pin 63 is in turn retained in position by the action of two clips 65 and 66 of identical construction except that one is right hand and the other is left hand. The clips 65 and 66 are positioned within the arm 1 and have at their upper ends small flanges fittable within slots 67-68 (67 not shown) cut in opposite sides of the operating arm 1 near the front thereof. The spring 64 resiliently maintains the small flanges on the clips 65-66 in position within the slots 68, thereby locating the pin and clips with respect to the operating arm 1. The clips 65 and 66 are provided with teeth 69-70, which normally engage with the offset teeth 29 and 30 on the magazine arm 2 to limit the movement of the operating arm 1 away from the magazine arm 2. By pressing inwardly on outwardly extending tabs T at the bottom of clips 65 and 66, the teeth 69 and 70 will be moved out of alignment with the teeth 29 and 30, respectively, and the operating arm 1 may be moved about the pintles 4a and 4b away from the magazine arm 2. The sloping edges of the teeth 29, 30, 69, and 70 are beveled so that they will knife by each other when the arm 1 is swung into operating position. Notches n₁ and n₂ in guides 33 and 34, notches n₃ (not shown) and n₄ in walls 25 and 26, provide clearance space permitting the tabs T to be moved inwardly. Notches n₅ (not shown) and n₆ in the walls of arm 1 accommodate the tabs T of the clips 65 and 66. A handle 71, shaped and recessed as shown in Figures 1 and 2, fits over the top of the operating arm 1 and is secured thereto by counter-sunk screws or other suitable fastening means. The handle 71 is preferably formed of transparent material. A card 72 bearing indicia is inserted between the top of the arm 1 and the handle 71. This card is of course interchangeable, and a card with appropriate insignia and indicia may be used as desired. The card is viewed through the handle which protects it from deterioration. The handle 71, however, may be made of other materials which produce a smooth surface and attractive appearance.

With the device positioned on a desk, and the base arm 3 resting flat thereon, to drive and

clinch staples, it is only necessary to apply force to the top of the operating or presser arm 1 or handle 71. The first action merely compresses both the operating arm 1 and the magazine arm 2 against the top of material inserted between the magazine arm and the anvil 5. Further compression causes the operating arm 1 to move downwardly relative to the magazine 2, thus forcing the staple driving blade 59 against the bridge of a staple, ejecting it downwardly between the wall 24 and the forward end of the core 23, whereby its legs are caused to pierce the material and be bent over in the clinching cavities formed in the top of the anvil 5. To assure this action the spring 20 has less effective compressive force than the two springs 55 and 56. When pressure is released the operating arm 1 is moved relatively away from the operating arm 2, and both of these arms are moved upwardly from the base arm 3 to assume the position shown in Figures 1 and 2. The relative movement between the arms 1 and 2 is limited by the engagement between the upper edges of the projections 27 and 28 and the top of the arm 1 in the down direction, and the engagement between the offset teeth 29 and 30 and the teeth 69 and 70 in the up direction. The total relative movement is sufficient to permit the edge of the driving blade to move a distance sufficiently in excess of the over-all length of the legs of the staples adapted for use in the machine to completely drive the same one by one from the magazine.

In the event that a staple is jammed, and it is necessary to obtain access to the interior of the magazine arm 2, it is only necessary to compress the tabs T, thereby disengaging the teeth 69 and 70 from the teeth 29 and 30, whereupon the operating arm may be moved about the pintles 4a and 4b upwardly and away from the magazine arm 2. Upon moving the operating arm 1 into operative relation with the magazine arm 2, the driver blade 59 is guided by the beveled portions 31 and 38 on the guides 33 and 34 and the beveled portion B on the edge of the forward wall 24. The beveled sloping portions on the teeth 29, 30, 69 and 70 guide those teeth laterally past each other until snapped into alignment by the action of the spring 64.

The flanges 14 and 15 on the supporting bracket 12 are of sufficient height so that the ends of the operating arm 1 and magazine arm 2, and the handle (when the follower rod is fully inserted), may readily clear the base arm 2 as the arms 1 and 2 are swung away from the base arm 3 about the pintles 4a and 4b. With the base arm 3 swung 180 degrees away from the arms 1 and 2, these arms may be used as a unit, and the device operated as a tacker device. That is, the staples are driven into material without clinching the legs, the action of the anvil 5 being eliminated. In other respects the device acts in identically the same manner as when the staples are being clinched as heretofore described.

If it is desired to operate the device as a plier-type stapler, the device may be grasped in the hand of the operator, the fingers encircling the narrow portion of the base arm 3 and the handle 71 resting in the palm of the hand between the fingers and the thumb. Merely squeezing the hand causes the material to be clamped between the arm 2 and the anvil 5. Further squeezing causes the arm 1 to drive the staple through the material and clinch the legs thereof against the anvil.

Because of the height of the supporting brack- 75

et 12 it is preferable to provide the magazine arm 2 with pressed-out portions 73 at the lower rear of the sides 25 and 26, respectively. These pressed-out portions have a sliding fit with the lower inner sides of the flanges 14 and 15 of the supporting bracket 12, thereby providing a guide to assure the proper alignment between the ejection chute and the cavities in the anvil 5.

Although there are shown and described certain specific embodiments of the invention, many modifications thereof are possible. The invention is not to be restricted except in so far as is necessitated by the prior art and by the spirit of the appended claims.

15 I claim:

1. A stapling machine comprising a magazine arm having an ejection chute at one end and a loading opening at the other end, said magazine arm at its loading end being provided with upwardly extending pivot holding portions, an operating arm overlying said magazine arm and having at one end a driving blade reciprocal in said ejection chute and at its other end pivot holes, a base arm underlying said magazine arm and having at one end a clinching anvil in alignment with said ejection chute and at the other end upwardly extending brackets adapted to straddle said magazine arm and operating arm, and means pivotally interconnecting all of said arms at a common axis.

2. A stapling machine comprising, a magazine arm, an operating arm and a base arm having a common pivotal connection at one end of each, a compression spring operable between said magazine arm and said operating arm, spring means for urging said magazine arm away from said base arm, a spring-biased clip on said operating arm, an offset tooth on said magazine arm engageable with said clip to limit the extent of the operation of said compression spring in forcing said operating arm and said magazine arm apart.

3. A stapling machine comprising, a magazine arm, an operating arm and a base arm pivoted at one end of each, said magazine arm comprising an elongated core forming a staple track, a member folded about said core from the forward end thereof and providing forward and side walls, the top edge of said forward wall being curved outwardly, guide members secured to said side walls and spaced from said core, the forward edges of said guide members being spaced from said forward wall and having their top corners beveled, said operating arm having a driving blade operable between said forward wall and said forward edges.

4. A stapling machine comprising, a magazine arm, an operating arm and a base arm pivoted at one end of each, said magazine arm comprising an elongated core forming a staple track, a member folded about said core from the forward end thereof and providing forward and side walls, the top edge of said forward wall being curved outwardly, guide members secured to said side walls and spaced from said core, the forward edges of said guide members being spaced from said forward wall and having their top corners beveled, said operating arm having a driving blade operable between said forward wall and said forward edges, said guide member having pedestals adjacent their rear ends, and springs acting between pedestals and said operating arm.

5. A stapling machine comprising, a magazine

arm, an operating arm and a base arm pivoted at one end of each, said operating arm comprising an elongated piece of metal folded about a forward wall to provide side walls, the top portions of said side walls being folded inwardly and interlocked by key and notch means formed integrally thereon.

6. A stapling machine comprising, a magazine arm, an operating arm and a base arm pivoted at one end of each, an operating handle positioned on said operating arm and substantially co-extensive therewith, said handle being of non-metallic transparent material, and an identification marking card positioned between said handle and said operating arm.

7. A stapling machine comprising, a magazine arm, an operating arm and a base arm pivoted at one end of each, means releasably holding said operating arm in relation to said magazine arm, a staple driver blade positioned in said operating arm and cooperable with said magazine arm

to drive staples therefrom, and means cooperably interengaged with said first mentioned means for holding said blade in operative position within said operating arm.

5. 8. A stapling machine comprising a magazine arm having an ejection chute at one end and a loading opening at the other, an operating arm overlying said magazine arm, a staple driving blade carried by said operating arm and operable in said ejection chute, a base arm underlying said magazine arm, a clinching anvil on said base arm in alignment with said ejection chute, means pivotally inter-connecting all of said arms at a common axis disposed adjacent said loading opening, and a feeder mechanism having a loose sliding connection with said magazine arm and operable within said loading opening to permit loading of the magazine without disconnection between the stapling machine and said feeder mechanism.

WILLIAM G. PANKONIN.
